UNITED STATES PATENT OFFICE.

TIMOTHY J. SULLIVAN, OF ALBANY, NEW YORK.

TRAP FOR WASTE-PIPES FOR BOWLS, &c.

SPECIFICATION forming part of Letters Patent No. 559,504, dated May 5, 1896.

Application filed August 15, 1895. Serial No. 559,342. (No model.)

To all whom it may concern:

Be it known that I, TIMOTHY J. SULLIVAN, a citizen of the United States, residing at Albany, in the county of Albany and State of New York, have invented certain new and useful Improvements in Traps for Waste-Pipes for Bowls, &c., of which the following is a specification.

My invention relates to traps for waste-water pipes leading from washbowls, closet-bowls, bath-tubs, &c.; and it consists of the combinations of devices and elements herein-after described, and set forth in the claims.

The objects of my invention are to provide for waste-water pipes a trap which will have both a water seal and a gas-tight valve, and connections for securing off and down, or direct lateral waste-pipes to the valve-case of the trap, and also for securing back-air connection-pipes to the said valve-case; also for providing a valve-case with a valve-guiding sleeve and a valve with a guiding-stem by means of which the valve will be guided in its vertical movements and be permitted to seat in a gas-tight manner on its seat; and further to provide a valve which will be simple, strong, and light and not liable to get out of order or become fouled by surface accumulations of foreign matters and be non-corrod़ing and having the quality to resist adhesion of substances which may be contained in the waste water.

Other objects and advantages of the invention will appear in the following description, and the novel features thereof will be particularly pointed out in the claims.

The invention is clearly illustrated in the accompanying drawings, which, with the letters of reference marked thereon, form a part of this specification, and in which—

Figure 1 is a sectional elevation of a vessel waste-water pipe, trap, and valve-case and its appurtenances embodying my improvements with back-air connection omitted. Fig. 2 is a sectional elevation of the trap and its appurtenances, on a smaller scale, with a back-air connection secured in place and illustrating my improvements. Fig. 3 is a sectional elevation, on like scale, illustrating a modification of a waste-pipe connection in connection with a trap embodying my improvements. Fig. 4 is a view taken at line 1, Fig. 1; and Fig. 5 is a view taken at line 2, Fig. 1.

In the drawings, A is the vessel from which waste water is to be run. A' is the usual connection thereof with a section of pipe B, which pipe is shown to have the usual slip-joint connection with the trap-body C. All the above-mentioned parts and devices employed therewith for connection of said parts in a watertight manner are so well known by the trade that a particular description of the same is unnecessary.

The upper end portion of the discharge-limb C' of the trap-body is provided with the pivot portion c, annular outwardly-projected flange c', and valve-seat c², provided with the end edge of the pivot portion c.

D is the valve-case, of any suitable form and calculated to inclose the valve. The lower end of this case D is provided with the downwardly-projected member E, provided with the external screw-thread e, and is secured to the pivot portion c of the discharge-limb of the trap-body by means of the coupling-nut F, usually employed for that purpose, and provided with a packing-ring e' for making a tight-joint connection. This valve-case is provided with the lateral projected member E', having an external screw-thread for use with a coupling-nut F' for securing a waste-pipe connection to said lateral projected member E'.

G is a vertically-projected member rising upwardly from the upper end of the valve-case D and integral with the same and having its bore relatively concentric with the valve-seat c², provided with the discharge-limb of the trap-body C. The inner side of this vertical member is provided with the screw-thread g and its outer side with the screw-thread g'. This member G serves four purposes: first, as a passage-way for communication between a back-air connection or pipe and the chamber of the valve-case; second, as a means for securing a valve-guiding sleeve in place relatively central with the valve-seat c²; third, as a means for securing a back-air connection with the valve-case, and lastly, as a means by which a closing-cap 100 may be employed for closing the said vertically-projected member G when a back-air connection is to be dispensed with.

H is a back-air connection-piece secured to the member G, projected from the upper end 105 of the valve-case D by means of the coupling-

nut H', as shown in Fig. 2, and having the joint between said member G and connection-piece H made gas and water tight by packing-ring h.

- 5 H² is a closing-cap, shown to be chambered for receiving the upwardly-projected end portion of a valve-guiding sleeve and screwing on the outside screw-thread g' when a back-air connection or pipe is to be dispensed with, 10 as is shown in Figs. 1 and 3. The joint between this closing-cap is made gas and water tight by means of a suitable packing-ring h, the same as employed for making a similar joint when the back-air connection-piece H is secured to the same sleeve by means of the coupling-nut H' above described.

I, Fig. 1, is an elbow-form connection which may be used in connection with the said valve-case of the trap when it may be advantageous 20 to run the waste-pipe B' vertically downwardly, as shown in Fig. 1.

I' is a lateral straightway-form connection, which may be used also in connection with the valve-case of the trap when it is desired 25 to run the waste-pipe laterally away from the trap, as illustrated in Figs. 2 and 3. By means of the coupling-nut F' and packing-ring f these pipe connections I or I' may each be secured to the laterally-projected member E' of 30 the valve-case in a water or gas tight manner when either of the same is selected to be employed for the purpose of connection with the waste-pipe to be carried downwardly or laterally for leading the water to a preferred 35 place of discharge.

J is the valve-guiding sleeve, which may be wholly or partly contained within the chamber of the valve-case D. This sleeve is securely supported in situation and position 40 so that the axial line of its bore may be about coincident with the center of the annular valve-seat c², and it is supported from member G, provided with the upper end of the valve-case, by means of the radial arms J' J', 45 integral with said sleeve and preferably connected with the outer ring portion J², provided with an external screw-thread j, corresponding with the internal screw-thread g and working in the same. This ring portion 50 J² may be omitted when the arms J', radiating from the sleeve J, are projected uniformly outwardly therefrom to a distance corresponding with the inside diameter of member G, as indicated by dotted and full lines in Fig. 5, 55 and have their ends provided with screw-threads for engaging with the said internal screw-threads g.

K is the valve, arranged within the chamber of the valve-case D and comprising the 60 disk k and central stem k'. The disk k of this valve is preferably made with a concavo-convex form and arranged with its convex side downward toward the discharge-opening of the limb C' of the trap-body and with its circumferential margin seated nicely on the seat c², formed with the end edge of the said limb, 65 as shown in Figs. 1, 2, and 3. Although this

valve with its stem may be made of any suitable metal, alloy, or substance, yet I at present consider the metal aluminium as being preferable to any other known substance heretofore 70 used for valves of waste-water traps, because of its quality of lightness, which permits the water flowing through the trap-body to readily raise the valve, its quality of non-corrosion of 75 surfaces, whereby the normal condition of surfaces may be preserved the same through its whole time of service, its quality for resisting the adherence of matters generally found in waste waters, and its quality to prevent accumulation of foreign matters, which heretofore has generally clogged the working portions of 80 valves of other material. The stem k' of this valve is cylindrical in form and corresponds with the diameter of the bore of the sleeve J, 85 within which it freely works without liability for lateral play. I also prefer to form the sleeve J of the metal aluminium.

Having described my invention, what I claim is—

1. In a trap for waste-pipes for bowls, &c., the combination with a valve-case provided with a downwardly-projected member, which is calculated to receive the discharge end of the trap, and with an upwardly-projected 95 member, adapted to have connected with it a back-air pipe and provided with an internal screw-thread, the discharge end of the trap being provided with a valve-seat c² and contained within said downwardly-projected 100 sleeve, of the vertical valve-guiding member having radial arms which allow an upward passage of water and are held by screw-threads with the internal screw-threads of the upwardly-projected member, and a valve provided with a central stem working in said valve-guiding sleeve, substantially as and for the purposes set forth.

2. In a trap for waste-pipes for bowls, &c., the combination with the valve-case D having with it the downwardly-projected and externally-screw-threaded member E, laterally-projected connection member E, adapted to have connected with it an elbow of a vertical waste-pipe, and the upwardly-projected member G provided with an internal screw-thread and adapted to be connected, at will, with a back-air pipe, of a valve-seat c² integral with the discharge end of the trap and contained within the bore of the downwardly-projected 110 member E, a valve-guiding sleeve J provided with radial arms, between which water may flow upwardly which are held by screw-threads with the internal screw-threads of said sleeve G, and a valve contained within 115 the valve-case and seating on said valve-seat c² and provided with a central stem working in the valve-guiding sleeve, substantially as and for the purposes set forth.

TIMOTHY J. SULLIVAN.
